UNITED STATES PATENT OFFICE.

JAMES G. MACLAREN, OF MAMARONECK, NEW YORK, ASSIGNOR, BY MESNE ASSIGNMENTS, TO THE LAMSON COMPANY, A CORPORATION OF MASSACHUSETTS.

PNEUMATIC-DISPATCH-TUBE APPARATUS.

Application filed April 6, 1920. Serial No. 371,728.

This invention relates to pneumatic carrier systems, being more especially concerned with pneumatic dispatch tube apparatus of that class in which a single transit tube is used for the transmission of carriers in opposite directions, and more particularly, systems of the type in which an air pressure above that of the atmosphere is utilized for the propulsion of the carriers.

10 My invention will be best understood by reference to the following description, when taken in connection with the accompanying drawings, while its scope will be more particularly pointed out in the appended claims.

15 In the drawings; Figure 1 is a plan view with one side sectioned on the line 1-1 in Figure 3. Figure 2 is a sectional elevation on line 2-2 in Figure 1, and there is also shown in this figure, an elevation of the timing dash pot to illustrate its location in relation to other parts. Figure 3 is an end elevation including a sectional view of the timing dash pot. Figure 4 is a sectional plan of the main casting, along line 4-4 in Figure 3. Fig. 5 is a view partly in side elevation and partly in section showing in detail a minimum pressure release valve mechanism, and Figure 6 is a diagram showing one form of a pressure pneumatic dispatch tube system.

20 Referring to the drawings, and to the embodiment of my invention which is illustrated therein, I have diagrammed in Figure 6, a pneumatic dispatch tube apparatus, comprising a transit tube 9 connecting two terminals 10, which may be, and are herein, identical in construction, though one is arranged for upward and the other for downward discharge of carriers. Each of these terminals is herein equipped with a chute 11 of the usual construction to check the speed of the emerging carrier, and to assist in bringing the latter to rest at a suitable point.

25 As a means for supplying an air current for the propulsion of the carriers through the transit tube, I have herein provided a power driven air compressor 12, which delivers compressed air through a pipe 13 into

a tank 14, having an outlet pipe 15 leading to a pressure regulating valve 16, of which there are many makes available in the open market, whence branch pipes 17 lead to the respective terminals 10.

30 Since the latter are herein of identical construction, a detailed description of one will suffice for both.

35 Referring now more particularly to Figures 1 to 4, inclusive, the terminal 10 is provided with a chamber 18 communicating in any suitable manner with the transit tube 9, the latter for this purpose being herein provided with one or more perforations 19. Communication between the air supply pipe 17 and the transit tube 9 may be controlled by any suitable valve, such for example, as a valve 20 hereinafter called "the air inlet valve", the latter cooperating with a suitable seat 21, and having a stem 22 mounted to slide vertically in a guide 23. Any suitable means may be provided for normally holding the valve 20 seated, but herein I have provided a helical spring 24 encircling the valve stem and serving in obvious manner to assist the air pressure in holding the valve seated except when it is purposely opened.

40 As a means for closing the carrier inlet (and outlet) of the transit tube, I have herein provided a suitable closure 25, usually called a door, of common form, usually made of rubber or some other suitable more or less yielding material, secured to a reinforcing plate 26 and carried on an arm 27. As a means for attaching the door to the arm, I have herein provided a bolt 28 passing through both, and encircling this bolt is a suitable spring 29, interposed between the plate 26 and the arm 27 and constantly tending to move the door 25 away from the arm 27 for purposes which will presently appear.

45 The door-carrying lever 27 is herein pivoted on a pin 30, and is interposed between a pair of ears 31 and rigidly secured thereto. As a means for normally holding the door open and automatically returning it to its open position after having been closed, I may provide any suitable means, such as a

spiral spring 32, attached at its inner end to the pin 30 and its outer end to the arm 27, although in the case of a downward discharging terminal this spring may be omitted if desired, and gravity alone relied upon to open the door. Pinned to the arm 27 is a buffer pad 33 and opposite it is a steel plate 34 projecting somewhat beyond the end of arm 27 for purposes as hereinafter explained.

The hinged end of the arm 27 is formed into a fork 35 and within this fork and free to rotate on the pin 30, is the valve lifter cam 36 on one end of which is the notched extension 37. The opposite wedge-like end 38 of the cam 36 is arranged to engage the head 39 of the valve stem 22. Spanning the ends of the fork 35 and secured thereto is a plate 40. Obviously, if the arm 27 is moved to the dotted position 27, the plate 40 will first engage the extension 37 on the cam 36 and then rotate the cam 36, thereby lifting the valve stem 22 and moving the valve 20 from its seat 21, thereby setting up a flow of air from the pipe 17 into the chamber 41 and through the passages 42' (Fig. 4) into the chamber 42 and beneath the opened valve 20 to the chamber 18 to the transit tube 9. The air also passes through the small hole 43 to the chamber 44, which is closed at one side by the flexible diaphragm 45 in the arrangement I am describing and have shown in the drawings.

Attached to the diaphragm 45 is a bell-crank lever 46 supported at one end in a yoke 47 and pivoted at its other end on a pin 48 passing through and supported in a pair of ears 49 extending from the ring 50. This ring 50 is preferably secured to the main casting of the terminal 10 with screws and serves to clamp the diaphragm 45 in place and to prevent leakage of air from the chamber 44. The catch 51 on the lever 46 is located to engage the extension 34 on arm 27 when in the dotted position. Obviously the force of the air pressure in the chamber 44 on the diaphragm 45, pushing on the free end of the lever 46, will lock the arm 27 in its dotted position, sealing the normally open end of the transit tube 9 with the door 25 and the external pressure of the spring 29 against the air pressure in terminal 10.

A handle 52 is pivotally supported by pin 30 and has an extension 53 faced on the inside with a buffer 54. A spiral spring 55 tends to rotate the handle 52 as hereinafter described, having its inner end secured to the pin 30 and its outer end to the under side of the handle 52.

Extending from one side of the handle 52 is an ear carrying a stud 56, located in relation to the pin 30 as indicated by the dotted lines 56 in Figure 2. Extending from this stud 56 is a link 57, on the other end of which is pivoted the piston 60 by means of the

pin 58 and yoke 59. The piston 60 slides in cylinder 61.

It will now be clear that if the handle 52 is manually rotated toward the end of the transit tube 9, it will first engage with the buffer 33 on the arm 27, which may in this manner be moved to the dotted position 27 to seal the outlet from the transit tube 9, it will also rotate the cam 36 to establish an air flow through the transit tube for the propulsion of carriers therethrough; and it will admit air pressure to the diaphragm 45 to lock the arm 27 and the door 25—26 in closed position.

Screwed into the main casting of the terminal 10 is a plug 62 which fills the opening at the top of chamber 42 provided to permit machining the seat 21 and to give access to the valve 20. To the shank 63 extending from the plug 62, is secured a bracket 64 held in place thereon by a screw or pin 65 passing through a hole in the bracket 64 into the shank 63. On the bracket 64 I prefer to provide a male thread 66 and onto this screw the cylinder 61.

The handle 52 being rotated to the dotted position 52 or beyond, and then released, it will be forced back to its normal position (shown in full lines) by the spring 55 and the movement of handle 52 will move the piston back and forth in the cylinder 61, the piston being linked to the handle.

From the end of the cylinder 61, beyond the piston 60, is a passage 67 leading to the atmosphere and into which is inserted a check valve and timer casing 68. Within the casing 68 is a passage 69 in communication with the passage 67. The upper end of the passage 69 is covered by a check ball 70 fitted to seat on and seal the passage 69. To retain the ball 70 in the casing 68, a plug 71 is provided, having a hole 72 through its center. The lower end of the casing 68 is shown fitted with a screw plug 73 and cut in the side of this plug 73, is a V groove 74 to serve as an air port for the passage of air into the passages 67 and 69. The shape of the groove 74 permits a nice adjustment of the port area by the distance the plug 73 is screwed into the housing 68.

The handle 52 may be freely rotated toward the transit tube, because the air in the cylinder 61 will be forced by the piston 60, through the passages 67 and 69, past the check ball 70 and out through the hole 72. The return of the handle 52 to its normal position however, can be timed by the location of the plug 73, which determines the amount of air the piston 60 may draw through the groove, or port 74 per unit of time and this unit of time is usually about equal to the time required to propel a carrier from one end of the transit tube 7 to the other end.

On the side of the terminal 10 is a rod 75 supported by an ear 76 near its left-hand

end as viewed in Fig. 1 and at the other end in a hole 77 through a boss 78. The left hand extremity of the rod 75 is normally in engagement with the extension 53 of handle 52, while its right hand end is connected to a valve 79 engageable with a seat 80 in the end of a passage 81 leading from the chamber 44. Screwed onto the end of the boss 78 is a cover 82 through which are holes 83. Between the inner end of the cover 82 and the valve 79 are a spring 84 and washers 85. The spring 84 tends to seat the valve 79 and the tension of this spring may be adjusted by the number and thickness 15 of washers 85 to balance the air pressure on valve 79 when it is closed on its seat 80 and the terminal is in operation.

When the handle 52 returns to normal position the extension 53 engages the rod 75 and the tension of spring 55 being by design sufficient to overcome the spring 84, the valve 79 is pushed from its seat, permitting the escape of air from the chamber 44 through passage 81 and holes 83 to the atmosphere faster than compressed air can enter through the small hole 43, thereby destroying the air pressure on the diaphragm 45 and causing the release of arm 27, which then is returned to normal position by gravity or the spring 32, or both, as may be desired.

It will be clear that the release of air pressure from the upper side of diaphragm 45 permits the weight of the gate member 27 assisted by the spring 29 to release the member 34 of the gate from the catch 51 whereupon the gate swings down to its open position.

The chamber 44 is preferably provided 40 with an additional outlet to permit the escape of air therefrom under certain conditions. Referring to Figs. 4 and 5, the valve casing is shown as provided with an outstanding boss 86 having an upper chamber 45 which communicates with the chamber 41 by means of a restricted passage 91 and having a lower chamber or cavity which opens freely into the outer air. These chambers are separated by a partition having a central guide aperture therein for the reception 50 of the guiding stem of a valve having a head 90 disposed in the upper chamber of the boss 86. This head normally rests upon an annular seat surface at the upper end of 55 the aperture and the guiding stem fits loosely in the aperture to permit leakage past the stem when the head is raised from its seat.

The bottom wall of the lower chamber in 60 the boss is furnished with a small opening 87 aligned with the guide aperture which receives the stem of the valve 90. The opening 87 connects the chamber 44 with the lower chamber of the boss 86. The opening 87 is normally closed by means of a disk 65 valve 88 which is held seated during nor-

mal operating conditions by means of a compression spring 89 which is interposed between this disk valve 88 and the lower end of the stem of the valve 90.

Under normal conditions the valve 90 is forced on its seat by the pressure in the upper chamber of the boss and the spring 89 is under sufficient compressive stress to hold the valve disk 88 against its seat, the effective area of the valve disk 88 being less than 75 the normal effective area of the valve head 90.

The air which acts upon the upper end of the valve 90 enters through the hole 91, the size of which is sufficient to overcome the loss at normal pressure past the valve 90 80 when the valve 90 is open. This valve 90 and its cylindrical body may be considered as a piston, the body of this valve fitting loosely in its bearing so that air may leak past it when the upper end of this valve is unseated. 85 Both the head and the body of the valve 90 are of greater cross-sectional area than the port 87. Normally the air pressure per square inch on the head of the valve 90 and on the valve disk 88 is the same. This pressure as above stated is normally sufficient to compress the spring 89, but if the pressure in the transmission system falls below normal due to operation of transmission lines in excess of the number for which the pump is 90 designed the pressure on the valve 90 will drop and the pressure on the spring 89 will 95 thus be relieved.

Under these conditions the valve 88 flutters and opens slightly so as to spill air from the small chamber 44 faster than air can pass the small hole 83 under the reduced pressure. In practice a very small release of pressure on the diaphragm 45 releases the door 25. It is necessary to exert some pressure on the valve 88 in order actually to seal the port 87, but the valve 88 never moves far from its seat.

When the head of the valve 90 rises the 110 available downward force is governed by the area of the cylindrical portion of the valve and the leakage past it. As the disk 88 is relieved of the spring pressure the very slight rise of this valve increases its effective pressure area so that the upward and 115 downward forces acting upon the spring are not substantially different in value.

When a normal pressure is restored in the 120 system the valve 90 moves downwardly compressing the spring and causing the disk 88 to approach more closely to its seat whereupon the effective pressure rapidly lessens and the valve 88 is firmly seated. This seating of the valve 88 is facilitated by the fact that following the door release and consequent closing of the main valve 20 there is 125 no pressure in the chamber 44 while normal maximum pressure acts on the valve 90. Thus the valve 90 acts with relatively greater 130 force downwardly than that acting upon the

disk 88 tending to push the latter upwardly and the disk is thus readily forced to its seat.

In single tube pressure systems, it is not the practise to provide air pump capacity sufficient to operate all the lines in the system, so it can happen that more terminals are cut into service than the pump can supply, creating a load condition beyond the capacity of the pump.

If too high a pressure is maintained in the system, the carriers will travel with such force, the bends may be driven out of the usual type of sleeve coupling used in the art, a particularly serious matter if the separated joint is in a concealed place. To prevent these conditions I have provided the valve mechanism shown in Figure 5, to automatically prevent closure of the transmission tube if the operating pressure drops below a determined point and the adjustable tension spring 84 to release the pressure on diaphragm 45 and thereby release latch 46 and allow the valve 20 to close to automatically cut off the air, if the operating pressure exceeds a safe limit. Carriers left in the line by the operation of either of these safety devices, will pick up and be discharged the next time the line is used.

As a means to regulate the air pressure in the transit tube, I employ a sleeve 92 having openings of a size and location corresponding with the holes 19 in the transit tube. By rotating the sleeve about the transit tube, the effective size of the openings through which air passes into the tube 9 from chamber 18, can be adjusted to meet the requirements of the individual line on which the terminal is used. Having been adjusted, the sleeve 92 is then clamped in place on the transit tube 9 by means of the clamp coupling 93, secured by the screws 94.

The air supply pipe 17 is joined to the terminal by means of the ball 95, shown in Figure 2 with a 90 degree segment omitted, which is screwed onto the pipe end and fits the seat 96 in the terminal 10 and is sealed therewith by the threaded collar 97.

To dispatch a carrier, it is inserted into the transit tube 9 and the handle 52 swung to place the door 25 over the end of the tube and to crowd the projection 34 past the catch 46 where it will be held by reason of the air pressure on the diaphragm 45, which pressure will have been established, together with a carrier propelling air flow, by the opening of the valve 20 in the act of closing the door as hereinbefore described.

The handle 52 being released, it will return to its normal position as rapidly as air can enter the dash pot through the port 74. As the handle nearly reaches its normal position, it engages the rod 75, venting the chamber 44, thereby unlatching the arm 27, which will immediately swing to its normal

position against the handle 52, releasing the valve 20 to cut off the air flow which will have been maintained sufficiently long to deliver a carrier, as previously explained.

Having thus described my invention, what I claim and desire by Letters Patent to secure is:

1. In a pneumatic dispatch tube system, a transmission tube, a closure member for an end of the tube, movable means separate from the closure member for engaging and moving the closure member to carrier-transmitting position, fluid pressure means made operable by pressure fluid in the tube system for holding the closure member in carrier-transmitting position and time controlled means independent of the pressure in the tube system for releasing the fluid pressure in said holding means to release said closure member at the end of a predetermined interval of time.

2. In a pneumatic dispatch tube system, a transmission tube, a hinged closure member for an end of the tube, a manually operable hinged closure operating member for moving said closure member into carrier-transmitting position, fluid pressure means made operable by pressure fluid from the tube system for holding the closure member in carrier-transmitting position, and fluid pressure operated time controlled means independent of the pressure in said tube system for retarding the return movement of the closure operating member to normal position, and means operated by said closure operated member when its normal position has been reached for releasing said holding means to thereby release said closure member.

3. Power control apparatus for a pneumatic dispatch system having a transmission tube and means for creating a carrier propelling air current therein, said apparatus comprising a casing provided with a socket for the reception of the end of the transmission tube and a chamber communicating with the tube through an opening in the side wall of the latter, a normally open pivoted cover for the end of the tube, a normally closed valve for controlling admission of pressure fluid to the chamber, a rotary valve lifter turning freely about the axis of movement of the cover and independent of the latter, and lost motion connections between the cover and said rotary valve lifter for moving the latter as the cover approaches its closed position and thereby opening said controlling valve.

4. Power control apparatus for a pneumatic dispatch system having a transmission tube and means for creating a carrier propelling air current therein, said apparatus comprising a casing provided with a socket for the reception of the end of the transmission tube and a chamber communicating with the tube through an opening in the side wall of the latter, a normally open

- pivoted cover for the end of the tube, a normally closed valve for controlling admission of pressure fluid to the chamber, a rotary valve lifter turning freely about the axis of 5 movement of the cover and independent of the latter, said actuator having a shoulder at one side of its axis and a valve lifting cam at the other side of its axis, and a member partaking of the swinging movement of the 10 cover normally spaced from the shoulder of the actuator but engageable with said shoulder as the cover approaches closed position and thereafter lifting the valve as the cover completes its movement.
- 15 5. Power control apparatus for a pneumatic dispatch system having a transmission tube and means for creating a carrier propelling air current therein, said apparatus comprising a casing provided with three 20 sockets arranged side by side, the central socket extending entirely through the casing and being adapted to receive the end portion of the transmission tube, one of the lateral sockets receiving the end of an air supply 25 pipe and the other socket receiving a removable plug supporting a timing device, said casing having a chamber into which the lateral sockets open, a normally closed valve controlling a passage between said chamber 30 and a second chamber which in turn communicates with the transmission tube by means of an opening in the side wall of the latter, a normally open cover for the end of the transmission tube, means actuatable by the 35 cover in closing to open said valve, and means controlled by the dash pot for terminating the period during which the cover remains closed.
6. Power control apparatus for a pneumatic dispatch system having a transmission 40 tube and means for creating a carrier propelling air current therein, said apparatus comprising a normally open cover for the end of the tube, fluid pressure controlled 45 latch means for retaining the cover in closed position during the transit of a carrier through the tube, a handle device independent of but engageable with the cover for moving the latter to closed position 50 where it is held by the latch, said handle tending to return to normal position after the cover is closed, a dash pot having a piston connected to the handle, said dash pot having valved air ports arranged to permit 55 free movement of the handle in closing the cover and to retard return movement of the handle to normal position, and a pressure relief valve actuatable by the handle as it reaches normal position to cause release of the cover holding latch.
- 60 7. Power control apparatus for a pneumatic dispatch system having a transmission tube and means for creating a carrier propelling air current therein, said apparatus comprising a normally open cover for 65
- the end of the tube, fluid pressure controlled latch means for retaining the cover in closed position during the transit of a carrier through the tube, a handle independent of but engageable with the cover for moving 70 the latter to closed position where it is held by the latch, said handle tending to return to normal position after the cover is closed, a dash pot cylinder, a piston in said cylinder, means connecting the piston to the handle, an 75 air control casing connected to one end of the dash pot cylinder, said casing having a chamber communicating with the cylinder, ports for said chamber, a valve permitting free egress of air from one port but preventing ingress of air through said port, an adjustable valve permitting a regulable amount of air to enter through the other port, said air control means permitting free 80 movement of the handle in closing the cover and retarding return movement of the handle to normal position, and a pressure relief valve actuatable by the handle as it reaches normal position to cause release of the cover 85 holding latch.
8. Power control apparatus for a pneumatic dispatch system having a transmission tube and means for creating a carrier propelling air current therein, said apparatus comprising a normally open cover for the 90 end of the tube, fluid pressure controlled latch means for retaining the cover in closed position during the transit of a carrier through the tube, and means for rendering the latch means inoperative when the pressure in the system is too high for effective 95 operation.
9. Power control apparatus for a pneumatic dispatch system having a transmission tube and means for creating a carrier propelling air current therein, said apparatus comprising a normally open cover for the 100 end of the tube, fluid pressure controlled latch means for retaining the cover in closed position during the transit of a carrier through the tube, and means for rendering the latch means inoperative when the pressure in the system is too high for effective 105 operation.
10. Power control apparatus for a pneumatic dispatch system having a transmission tube and means for creating a carrier propelling air current therein, said apparatus comprising a normally open cover for the 110 end of the tube, fluid pressure controlled latch means for retaining the cover in closed position during the transit of a carrier through the tube, and means for rendering the latch means inoperative when the pressure in the system is too low for effective 115 operation.
11. Power control apparatus for a pneumatic dispatch system having a transmission tube and means for creating a carrier propelling air current therein, said apparatus comprising a normally open cover for the 120 end of the tube, fluid pressure controlled latch means for retaining the cover in closed position during the transit of a carrier through the tube, and means for rendering the cover retaining means inoperative when the pressure in the system is either above or 125 below that necessary for effective operation.
12. Power control apparatus for a pneumatic dispatch system having a transmission tube and means for creating a carrier propelling air current therein, said apparatus 130

comprising a normally open cover for the end of the tube, fluid pressure controlled latch means for retaining the cover in closed position during the transit of a carrier through the tube, and means comprising a pair of valves of relatively different area controlling the operation of the fluid pres-

sure controller for the cover retaining latch whereby to render said latch inoperative when the pressure in the system falls below normal.

In testimony whereof, I have affixed my signature.

JAMES G. MACLAREN.
